UNITED STATES PATENT OFFICE.

JOSEPH C. DONNELLY, OF BARBERTON, OHIO, ASSIGNOR TO THE DIAMOND MATCH COMPANY, OF CHICAGO, ILLINOIS, A CORPORATION OF ILLINOIS.

BOX-FILLING MACHINE.

Application filed May 12, 1925. Serial No. 29,801.

This invention relates to box filling machines, and more especially to mechanism whereby box trays are supplied to the successive holders of an intermittently traveling carrier by means of which the trays are conveyed to the various stations of the filling machine.

The object of my invention is to provide simple and efficient mechanism whereby the box trays are positively and accurately advanced along a trough having a horizontal portion parallel with the path of the carrier and a curved delivery portion leading to such path, which mechanism comprises two spaced apart box-engaging members whereof one is operative to engage the successive boxes and feed them along the horizontal portion of the trough, and whereof the other member is operative with the first-named member and is arranged to engage the successive leading boxes and swing them through the curved portion of the trough and to position for delivery into the succeeding holders of the carrier; as will be hereinafter described and claimed.

In the drawings—

Figure 1 is a plan of a portion of a match box filling machine embodying my invention.

Fig. 2 is a longitudinal vertical section, as on the line 2—2 of Fig. 1.

Fig. 3 is a transverse vertical section, enlarged, as on the line 3—3 of Fig. 1.

Fig. 4 is a perspective view of the two feed members and their connections, showing a section of the trough, box trays therein and the members engaged with the adjacent trays.

Referring to the drawings, 5 designates a portion of the bed or table of a filling machine, and 6 a portion of the upper run of the intermittently-movable tray carrier of the machine, which carrier comprises an endless chain of holders 7 constructed and arranged to receive the trays, 8, in succession and convey them along the bed or table to a station where the trays are filled with matches or other articles.

Arranged on the bed or table, and laterally of the carrier, is a tray guiding trough into the receiving end of which the trays in end to end relation are advanced from a suitable source of supply. This trough comprises a main body portion 9 extending parallel with the upper run of the carrier and

terminating in a curved delivery portion 10 of suitable radius and length leading to or adjacent the horizontal path of the tray holders.

Spaced from and parallel with the outer side of the trough body 9 is a rail 11 which in conjunction with the outer side of the trough slidably supports a plate 12 having at one end a bracket member 13 which overhangs the receiving portion of the trough. The plate is provided on its under side with a guide rib 14 slidably fitted in the way or space formed between the trough and the rail 11. On the bracket member is pivoted a push pawl 15 which normally gravitates into the underlying tray within the trough.

The plate 12 is flexibly connected by means of a rod 16 with one end of an oscillatory radius arm 17 which overhangs the juncture of the main body of the trough with the curved end portion 10, and is movable in an arc substantially concentric with that of the said end portion. This plate pivotally supports a push pawl 18 which normally gravitates into the underlying tray within the curved portion. Hence the two pawls are simultaneously actuated by the operation of the arm 17.

This arm is secured to the upper end of a vertical shaft 19 journaled in a bearing 20 supported on and depending below the table. Fixed on the lower end of the shaft is a sector gear 21 in mesh with a similar gear 22 on a shaft 23 which is journaled in hangers 24 below the table.

Fast on this shaft 23 is a depending arm 25 which is provided at its lower end with a roll 26 extending into the race of a cam 27 on a suitably-disposed driven shaft 28. This shaft bears a gear 29 in mesh with a gear 30 on the main drive shaft 31 of the machine. The contour of the cam race is such that the arm 25 is oscillated in timed relation to the travel of the carrier; thus rocking the shaft 23 and effecting, through the sector gearing and connections described, the oscillation of the radius arm 17 and, perforce, the simultaneous reciprocation of the two pawls, one moving in a straight path at the receiving end of the trough and the other in a curved path at the discharging end of the trough.

The pawls in their forward strokes advance the respective trays engaged thereby, and in their return strokes ride upon the rearward ends of the engaged trays and en-

ter the next succeeding trays, respectively, and so on. Hence the trays are intermittently pushed, in train, along the straight and curved portions of the trough by the respective pawls. The timed relation of the travel of the pawls to that of the carrier is such that the leading trays in the curved portion of the trough are positively entered into each succeeding holder during the dwell 10 of the latter in its intermittent movement.

I claim—

1. In a box-filling machine having an intermittently movable carrier for match trays, a tray supply trough located laterally and extending longitudinally of the carrier and having a curved delivery portion of sufficient radius and length leading to the path of the carrier, a push pawl adjacent the receiving end of the trough, a reciprocating support for said pawl, means for guiding said member parallel with the body of the trough, a push pawl adjacent the curved delivery portion of the trough, a radius arm carrying the latter pawl and movable in an arc substantially concentric with that of the said delivery portion of the trough, a rod flexibly connecting said arm with the said support, and means for

oscillating said arm in timed relation to the travel of the carrier.

2. In a box-filling machine having an intermittently movable chain of tray holders, a tray-supply trough located laterally and extending longitudinally of the chain and having a curved delivery portion of sufficient radius and length leading to the path of the holders, a push pawl adjacent the receiving end of the trough, a reciprocating member supporting said pawl, means for guiding said member parallel with the body of the trough, a push pawl adjacent the curved delivery portion of the trough, a radius arm carrying the latter pawl and movable in an arc substantially concentric with that of the said delivery portion of the trough, a pivot shaft for said arm, a rod flexibly connecting said arm with the reciprocating member, a rock-shaft, gearing between the two shafts, and cam connections for actuating the rock-shaft in timed relation to the travel of the carrier.

Signed at Barberton, in the county of Summit and State of Ohio this 7 day of May, A. D. 1925.

JOSEPH C. DONNELLY.
